UNITED STATES PATENT OFFICE.

DANIEL L. HARRIS, OF WICHITA, KANSAS.

DRINKING-FOUNTAIN AND WASTE-RECEPTACLE.

1,141,794.

Specification of Letters Patent.

Patented June 1, 1915.

Application filed July 22, 1914. Serial No. 852,459.

To all whom it may concern:

Be it known that I, DANIEL L. HARRIS, a citizen of the United States, residing at Wichita, in the county of Sedgwick and State of Kansas, have invented new and useful Improvements in Drinking-Fountains and Waste-Receptacles, of which the following is a specification.

An object of the invention is to provide a drinking fountain for use in public places or stores, for supplying drinking water and which also contemplates a waste receptacle to receive waste matter.

The invention contemplates, among other features, the provision of a fountain which will present a neat and effective appearance and which is artistically designed and constructed to supply drinking water, and which further includes a cuspidor for persons desiring to expectorate, thus having the expectorant received in a suitable drain, with means for keeping the receptacle adapted to receive the expectorant in a clean and sanitary condition.

The invention still further comprehends the provision of a fountain having a receptacle adapted to receive waste paper and waste matter, and thus it will be apparent that the drinking fountain, particularly when in a public place, will present a device which not only contemplates the use of individual sanitary drinking cups, but which also will do away to a great extent, with persons expectorating on the street and, furthermore, presents a structure in which persons will place waste paper and waste matter rather than throw the same upon the highway.

Still further embodiments of the invention reside in a drinking fountain, parts of which can be devoted to advertising purposes and the like.

In the further disclosure of the invention reference is to be had to the accompanying drawings, constituting a part of this specification, in which similar characters of reference denote corresponding parts in all the views, and in which:

Figure 1 is a perspective view of the fountain; Fig. 2 is a vertical sectional view taken through the fountain; Fig. 3 is a vertical sectional view taken on the line 3—3 in Fig. 2; Fig. 4 is a detail plan view; and Fig. 5 is a horizontal sectional view taken on the line 5—5 in Fig. 3.

Referring more particularly to the views, I provide a base or pedestal 10 supporting a

substantially hollow body 11 on the upper end of which is carried a bowl 12 constituting a cuspidor, the body 11 having a side thereof formed with a door 13 communicating with the interior of the body 11 and which provides a waste paper compartment 14, suitable openings in the nature of chutes 15 being provided in order that the waste paper may be dropped into the compartment 14. A drain pipe 16 has connection with the bowl 12 and passes downwardly through the waste paper compartment 14 and also passing through the waste paper compartment 14 is a water supply pipe 17 having a suitable valve 18 preferably arranged within the base 10, access to the valve being had by a suitable closure 19 on the base.

A plurality of opposed arches 20 are supported on the bowl 12 and project upwardly to support a second hollow body 21, the upper end of which carries a receptacle 22 in which gold fish can be kept, or plants or other ornamental bodies or devices can be arranged. A plurality of opposed faucets 23 are supported on the receptacle 22 and project exteriorly thereof, said faucets having connection with the upper end of the pipe 17 and which passes through one of the arches 20, said arch being made hollow to accommodate the pipe 17 as mentioned and shown. Thus it will be seen that when the valve 18 is turned on the supply of water will be carried through the pipe to the valves 18 and which, when opened, will permit the water to flow therefrom.

Cup supporting and drain members 25 are secured to or formed with the body 21 and arranged immediately beneath the faucets 23 so that a cup supported on one of the members 25 will be in position to receive water from the faucet above the same when the faucet is turned on. The cup and drain supporting members 25 communicate with a flared head 26 of a pipe 27 which, passing downwardly in the body 21, communicates with the other arch 20 which is preferably made hollow in the nature of a pipe. The lower end of this arch communicates with a circular perforated spray pipe 28 which is preferably formed along the rim of the bowl 12 and which may be also formed by bending the upper edge of the bowl around in the nature of a pipe.

Now it will be apparent that when a person has partaken of the water from the fau-

set by means, preferably, of a sanitary drinking cup made of paper or the like, the water remaining in the cup and which is not used by the person, is dumped or poured into 5 one of the cup supporting and drain members 25 and will thence pass into the head 26 and pipe 27, from which it will pass through the last mentioned arch 20 into the spray pipe 28, from which it will spray into the bowl 12, 10 thus cleaning the bowl of any expectorant which may have been previously discharged thereinto. The drain water which cleans the bowl and the expectorant will then be washed downwardly in the drain pipe 16 15 and can be carried off by any suitable pipe having connection with the drain pipe and leading to a sewer or the like.

Thus it will be seen that with a drinking fountain of the character described the 20 water which is not used for drinking purposes, will, through the unique construction of the device, be used as a means for keeping the cuspidor in a clean and sanitary condition. The usual sanitary drinking cups 25 which are used and which are adapted to be discarded after they have been once used, are, after they have been used, dropped into one of the chutes 15 to be received in the waste paper compartment 15 formed by 30 the body 11.

The faces of the body 11 which are indicated by the numeral 29 are preferably covered with glass or some other suitable medium, and can be readily employed for advertising purposes to receive suitable signs or inscriptions and, similarly, portions of the faces of the body 21, indicated by the numeral 30, can be used for advertising purposes, other portions of the faces of the 35 body 30 being preferably in the nature of mirrors, as indicated by the numeral 31, whereby the entire fountain, when complete, will present a neat and effective appearance.

Having thus described my invention, I 40 claim:

1. In a fountain, the combination with a bowl, of arches projecting from the bowl, a body supported on the arches, faucets on the body, a water supply pipe connecting 45 with the faucets, and passing through one of the arches, draining members on the body communicating with the other arch, and positioned to receive drip from the faucet whereby to drain therethrough into the bowl 50 any waste water from the faucet, and a drain pipe connecting with the bowl and depending therefrom to receive from the bowl the discharge water and any foreign substances contained in the bowl.

2. In a fountain, the combination with a

base, of a hollow body thereon, a bowl supported on the hollow body, hollow arches on the bowl, a second hollow body on the arches, a water supply pipe in the base and extending through the lower hollow body and 65 one of the arches, faucets on the upper hollow body and connecting with the pipe therein for conducting the water to the faucets, a drain pipe in the lower hollow body and connecting with the bowl, draining 70 members on the upper hollow body to receive any waste fluid discharged from the faucet, and a pipe in the upper hollow body and having the draining members communicating therewith, said pipe connecting 75 with the other hollow arch to conduct the waste water into the said bowl.

3. In a fountain, the combination with a base, of a hollow body thereon, a bowl supported on the hollow body, hollow arches on the bowl, a second hollow body on the arches, a water supply pipe in the base and extending through the lower hollow body and one of the arches, to the upper hollow body whereby water can be conducted to the 80 upper hollow body, faucets on the upper hollow body connecting with the pipe therein for conducting the water to the faucets, a drain pipe in the lower hollow body connecting with the bowl, draining members on 85 the upper hollow body to receive any waste fluid discharged from the faucet, a pipe in the upper hollow body having the draining members communicating therewith, said pipe connecting with the other hollow arch 90 to conduct the waste water into the said bowl, and a perforated sprayer pipe in the bowl connecting with the last mentioned hollow arch whereby the waste water from the drain members will be sprayed into the 95 100 bowl.

4. In a fountain, a base, a plurality of superposed hollow bodies on the base, a bowl interposed between said bodies and supported by one of them, arches on the bowl supporting the other body, faucets on the other body, a supply pipe passing through the bodies and communicating with the faucets, drain pipes adapted to receive the drip from the faucets and communicating with the 110 bowl, and a drain pipe communicating with the bowl and passing downwardly through the first mentioned body and said base.

In testimony whereof I affix my signature in presence of two witnesses.

DANIEL L. HARRIS.
